UNITED STATES PATENT OFFICE.

HENRY G. ELFBORG, OF CHICAGO, ILLINOIS, ASSIGNOR TO AJAX RAIL ANCHOR CO., OF CHICAGO, ILLINOIS, A CORPORATION OF DELAWARE.

ANTI-RAIL-CREEPER.

1,088,976.

Specification of Letters Patent.

Patented Mar. 3, 1914.

Continuation in part of application Serial No. 778,680, filed July 12, 1913. This application filed November 28, 1913. Serial No. 802,574.

To all whom it may concern:

Be it known that I, HENRY G. ELFBORG, a citizen of the United States, residing at Chicago, in the county of Cook and State 5 of Illinois, have invented certain new and useful Improvements in Anti-Rail-Creepers, of which the following is a specification.

My invention consists of an improved device for preventing the longitudinal creeping of the rails of a railway track relative to the ties.

This application is in part a division of my former application, Serial No. 778,680, 15 filed July 12, 1913, for anti-rail creepers which resulted in Patent 1,083,603, dated Jan. 6, 1914.

The objects and advantages of my improved device are fully set forth in the following description and claims and illustrated in the drawings.

Among the objects of my invention are the simplification of a device of this kind, a reduction in the number of parts, and in the 25 amount of material necessary in constructing the same, without sacrifice of efficiency.

A further object is the improvement in the operation of the device by securing a greater frictional contact between the stationary anti-creeper device and the rail to which it is applied.

It will be apparent from the following description and drawings, that this anti-rail creeper exerts a transverse pressure on the 35 edges of the rail base as well as a frictional contact between the lower side of the rail base and the upper surface of one member of my anti-creeper structure.

Referring to the drawings—Figure 1 40 shows a cross section of a rail with my improved anti-creeper assembled and applied thereto. Fig. 2 is a plan view of the same. Fig. 3 is an elevational view of the main member of my improved anti-creeper. Fig. 45 3^a is an elevational view of a slight modification of the member shown in Fig. 3. Fig. 4 is a plan view of the main member shown in Fig. 3. Fig. 4^a is a plan view of the modified member shown in Fig. 3^a. Fig. 5 is an end 50 view of the main member shown in Fig. 3. Fig. 6 is a plan view of the second or wedge member of my improved anti-creeper. Figs. 7 and 8 are views of the opposite ends of the wedge member shown in Fig. 6. Fig.

9 is a side elevation of the wedge member; 55 and Fig. 10 is a perspective view of the wedge member. Referring to the drawings, it will be seen that my invention consists substantially of two elements, a main member designated A and a second or wedge 60 member designated B.

The main member A is formed at one end with an upturned lip or jaw 1 which is in-turned, as shown at 2, to embrace the edge and part of the upper surface of the rail 65 base. The main member A is adapted to extend beneath and in contact with the lower surface of the base of the rail 3 and projects beyond the opposite edge of the rail base. At the end opposite the jaw 1—2, the 70 member A is provided with an up-standing shoulder 4, the inner, substantially vertical face 5 of which converges toward the edge of the rail base in the direction of the adjacent tie 7, against which the downwardly 75 extending abutment 8 on the main member is adapted to bear.

The under side of the end of the member A, opposite the lip or jaw 1—2, is provided with a surface 11 which inclines downwardly 80 toward the adjacent tie 7. I, preferably provide the member A with strengthening ribs 12, which may be terminated in shoulders 13 adjacent the inner boundary of the surface 11.

The second or wedge member B has in a general way the form of a box open along one side and at one end. The opening or slot 17 along the side of the wedge member has its lower face 11' inclined to correspond to the inclination 11, on the lower side of the wedge end of the main member A. From the upper wall of the opening or slot 17, along the side of the wedge member, there depends a rib 18 having along its inner 95 face an inclined surface 5' corresponding in inclination to the inclined surface 5 upon the main member A. The wedge member is preferably closed at the end 19, this end being shown in Fig. 7, but at the opposite end 100 the slot or opening 17 extends completely through the end 20 of the wedge member, the end 20 being shown in Fig. 8 of the drawings. The wedge member is recessed at 22 above the opening 17 forming the lip 105 23 adapted to overlie the edge of the rail base.

In assembling the device, the first mem-

ber A is placed under the rail with its lip or jaw 1-2 embracing one edge of the base thereof and with the abutment 8 against one of the ties, the device being placed on that side of the tie from which the greatest volume of traffic moves. This position of the first member is best shown in Fig. 1 and the proximity of the adjacent tie is best indicated in Fig. 2.

10 The second member B is then mounted on the first member A by passing the open end 20 of said second member B over the wedge end of member A from the side thereof, shown in Fig. 3, with the surface 5 coacting with the surface 5' and the surface 11 coacting with the surface 11'. The coaction between the surfaces 5 and 5' causes the rail base to be gripped transversely between the wedge member B and the upstanding lip or jaw 1-2 at the opposite end of the first member. The coaction between the surfaces 11 and 11', when the wedge member B is impelled toward the tie, has the effect of forcing or drawing the main member A upward toward the rail by reason of the fact that the lip 23 of the wedge member overlies the edge of the rail base while the surface 11' inclined downwardly toward the tie forces the main member A upward, as the wedge member moves toward the tie.

In practice the members A and B are castings having unfinished wedging surfaces so that the initial assemblage, as the abutment 8 upon the main member bears against a tie, toward which the traffic is moving, the movement of the wedge member B when forced toward the tie may, owing to the roughness or irregularity of the said coacting surfaces, cause the wedging surface 5' to seat and bind on the wedging surface 5 before the other wedging surface 11' on the wedge member has seated on the surface 11 on the main member, or before it has forced the main member into binding contact with the under surface of the rail. At this period in the adjustment of the anti-creeper, a transverse pressure only will be exerted on the lateral edges of the rail base. When the wedge member is driven further toward the tie it will have the effect of stretching or extending the main member A in the direction of the arrow 25 in Fig. 1 by virtue of the elasticity of the material of which it is constructed until the wedging surface 11' has seated on the surface 11, at which stage in the adjustment, a vertically acting pressure will be set up between the member A and the rail, the creeping of the rail thus being retarded by the frictional resistance on the bottom thereof as well as by the horizontal gripping of the edges of the base. On the other hand, should the wedging surface 11' seat first, the wedge member when driven further toward the tie will cause a spreading apart of said wedge member in

the direction of the arrows 24 in Fig. 8 by virtue of the elasticity of the material, which further movement of the wedge member B toward the tie causes the wedging surface 5' to seat on the surface 5 on the main member A, thereby causing a transverse gripping of the base of the rail.

Referring to Figs. 3^a and 4^a I preferably provide the ribs 12' of a lesser depth from a point adjacent the end thereof having the overhanging jaw or lip 1'-2' to the inclined under surface 11^a as shown at 14. This serves to weaken the member adjacent the said jaw so that any bending which may take place in the member A by virtue of the pressure exerted thereon will occur near the jaw, thus leaving the central portion of the member A with a flat upper surface and affording the largest possible frictional resistance to the creeping of the rail. I preferably also recess the upper surface of the member A, shown at 16, in order to allow ample clearance for the edge of the rail base under the lip or jaw 1'-2'. The abutment 8' may be located approximately at the center of the rail, as shown in Figs. 3^a and 4^a. This modified main member is also provided on its under side near the center of the end opposite the jaw 1'-2' with a depending lug 15 forming a shoulder 15^a adjacent the inner boundary of the inclined under surface 11^a, against which the lower wall of the wedge member is adapted to bear, thereby preventing any rotative movement of the latter member about an axis substantially parallel to the axis of the rail.

From the foregoing description it will be apparent that I provide a cheap and simple rail anchor, capable of being easily adjusted to the rail and having two independent sets of coacting wedging surfaces which set up a wedging action transversely on the rail base and also vertically between the rail base and the rail anchor, thus furnishing a very large frictional resistance to the creeping of the rail.

I have described in detail a particular form of my invention, but the invention is not limited to this particular form, inasmuch as the principle thereof may be embodied in structures of widely divergent form. For instance, it will be obvious that by reversing the inclination of the wedging surfaces the device might be used with the wedge member abutting against the tie instead of having the main member abut against the tie.

What I claim is:

1. An anti-creeper for railroad rails comprising a member adapted to underlie the base of a rail and to bear against a tie, one end of said member being adapted to hang upon and engage the rail base by means of an upwardly extending part directly engaging the edge of the rail base, and the other end of said member having an up-

wardly extending shoulder converging in a horizontal plane with the opposite edge of said rail base toward said tie, said last mentioned end of said member having also

- 5 a surface on its under side inclining downwardly toward said tie, and a second member adapted to overlie the other edge of the rail base and to embrace the last mentioned end of said main member by means of a
10 groove extending along one side thereof, said groove having one part adapted to coact with said upwardly extending shoulder of said main member and having another part adapted to coact with said inclined un-
15 der surface of the main member, whereby when said wedge member is impelled toward said tie the opposite edges of the rail base are clamped between said wedge member and the upwardly extending part of the op-
20 posite end of said main member and said main member is forced upwardly against the under side of said rail base.

2. An anti-creeper for railroad rails comprising a member adapted to underlie the base of a rail and to bear against a tie, one end of said member being adapted to hang upon and engage the rail base by means of an upwardly extending part directly en-
25 gaging the edge of the rail base and the other end of said member having an up-
30 wardly extending shoulder converging in a horizontal plane with the opposite edge of said rail base toward said tie, said last men-
35 tioned end of said member having also a
40 surface on its under side inclining downwardly toward said tie, and a second mem-
45 ber having a groove along one of its sides and extending through one end thereof, the upper wall of said groove being adapted to engage and overlap one edge of the rail base, a lug depending from the upper wall of said groove having an inner surface adapted to coact with the inner surface of said upwardly extending shoulder of said
50 main member and the lower wall of said groove being adapted to coact with the in-
55 clined under surface of the main member, whereby when said wedge member is im-
60 pelled toward said tie the opposite edges of the rail base are clamped between said wedge member and the upwardly extending part of the opposite end of said main mem-
65 ber and said main member is forced up-
70 wardly against the under side of said rail base.

3. An anti-creeper for railroad rails comprising one member adapted to underlie and engage one edge of the base of a rail and to bear against a tie, the other end of said member having two inclined surfaces, and a second member having a groove on one of its sides, said groove having two inclined wedging surfaces adapted to coact with the two inclined surfaces on said first mentioned member whereby when said second member

is impelled toward the tie the rail base is subjected to a transverse gripping and to a vertical pressure on its under side.

4. An anti-creeper comprising a rail, a member having a jaw engaging the upper side of and vertically supported by one edge of the base of said rail and extending beneath and in contact with said rail, and a second member engaging the upper surface of the opposite side of said rail base and having a groove along one of its sides adapted to engage the end of said first named member opposite the jaw thereon, one of said members being adapted to abut against an adjacent tie, said members having two pairs of coacting surfaces, each inclined longitudinally of said rail, the relative movement of said members acting through one pair of said inclined surfaces to grip the opposite edges of said rail base and through the other pair of inclined surfaces to force said first named member against the bottom of said rail base.

5. An anti-creeper comprising a rail, a member having a jaw engaging the upper side of and vertically supported by one edge of the base of said rail and extending beneath and in contact with said rail, the other end of said member having two inclined surfaces, said member being provided on its under and outer surface with depending ribs extending transversely of the rail, and a second member engaging the end of said first named member opposite said jaw by means of a groove along one of its sides, said groove having parts adapted to coact with said inclined surfaces on said first named member, whereby when said second member is impelled toward the tie the rail base is subjected to a transverse gripping and to a vertical pressure on its under side.

6. An anti-creeper for railroad rails comprising a main member adapted to underlie and engage one edge of the base of a rail and to bear against a tie, the other end of said member having two inclined surfaces, and a second member adapted to engage the last mentioned end of said main member by means of a groove along one of its sides, said groove having two inclined wedging surfaces adapted to coact with the said inclined surfaces on said main member, said second member being provided on its outer surface with projecting ribs, said ribs lying in planes approximately at right angles to the axis of the rail, the relative movement of said members acting to subject the rail base to a transverse gripping and to a vertical pressure on its under side.

7. An anti-creeper comprising a rail, a member having a jaw engaging the upper side of and vertically supported by one edge of the base of said rail and extending beneath and in contact with said rail, the other end of said member having two inclined

surfaces, said member being provided on its under and outer surface with depending ribs extending transversely of the rail and being of relatively greater depth around the outer surface of the said upwardly extending jaw, and a second member engaging the end of said first named member opposite said jaw by means of a groove along one of its sides, said groove having parts adapted to coact with said inclined surfaces on said first named member, whereby when said second member is impelled toward the tie the rail base is subjected to a transverse gripping and to a vertical pressure on its under side.

8. An anti-creeper for railroad rails comprising one member adapted to underlie and engage one edge of the base of a rail and to bear against a tie, the other end of said member having an upwardly extending shoulder converging in a horizontal plane with the opposite edge of said rail base toward said tie, said last mentioned end of

said member having also a surface on its under side inclined downwardly toward said tie, a lug depending from the under side of said member adjacent the inner boundary of said inclined under surface, and a second member having a groove on one of its sides, said groove having two inclined wedging surfaces adapted to coact with the two inclined surfaces on said first mentioned member, the lower wall of said groove being adapted to abut against the said depending lug on the under side of said first mentioned member, whereby when said second member is impelled toward the tie the rail base is subjected to a transverse gripping and to a vertical pressure on its under side.

In testimony whereof, I have subscribed my name.

HENRY G. ELFBORG.
